US0D1070598S

(12) **United States Design Patent** (10) **Patent No.:** **US D1,070,598 S**
(45) **Date of Patent:** **** Apr. 15, 2025**

(54) **BOTTLE**

(71) Applicant: **OnMyWhey, LLC**, Burlingame, CA (US)
(72) Inventors: **Farbod Deylamian**, New York, NY (US); **David Jacobsen**, San Diego, CA (US); **Kyle Lewis**, San Mateo, CA (US); **Kayvon Pourmirzaie**, San Jose, CA (US)

(73) Assignee: **OnMyWhey, LLC**, Burlingame, CA (US)

(**) Term: **15 Years**

(21) Appl. No.: **29/928,703**

(22) Filed: **Feb. 14, 2024**

Related U.S. Application Data

(63) Continuation of application No. 29/846,177, filed on Jul. 14, 2022, now Pat. No. Des. 1,021,628, which is (Continued)

Assistant Examiner — David Truong

(57) **CLAIM**

The ornamental design for a bottle as shown and described.

DESCRIPTION

FIG. 1 is a first perspective view of a bottle.

FIG. 2 is a second perspective view of the bottle shown in FIG. 1.

FIG. 3 is a front view of the bottle shown in FIG. 1.

FIG. 4 is a back view of the bottle shown in FIG. 1.

FIG. 5 is a left view of the bottle shown in FIG. 1.

FIG. 6 is a right view of the bottle shown in FIG. 1.

FIG. 7 is a top view of the bottle shown in FIG. 1.

FIG. 8 is a first perspective exploded view of the bottle shown in FIG. 1; and,

FIG. 9 is a second perspective exploded view of the bottle shown in FIG. 1.

The broken lines in the drawings depict portions of the bottle that form no part of the claimed design.

1 Claim, 9 Drawing Sheets

Related U.S. Application Data

a continuation of application No. 29/705,802, filed on Sep. 16, 2019, now Pat. No. Des. 959,987, which is a continuation of application No. 29/587,289, filed on Dec. 12, 2016, now Pat. No. Des. 844,435, and a continuation of application No. 29/587,298, filed on Dec. 12, 2016, now Pat. No. Des. 844,436.
